(57) CLAIM

I claim the ornamental design for a mounting trim for a barbecue grill, as shown and described.

DESCRIPTION

FIG. 1 is a perspective view of the mounting trim for a barbecue grill shown with the environment in broken lines. FIG. 2 is a perspective view of the mounting trim for a barbecue grill.

FIG. 3 is an atop plan view of the mounting trim for a barbecue grill.

FIG. 4 is a side view of the mounting trim for a barbecue grill, the opposite side being identical, and

FIG. 5 is an end elevational view of the mounting trim for a barbecue grill the opposite side and being identical.

1 Claim, 2 Drawing Sheets
